ELECTRIC DISCHARGE DEVICE

Filed Dec. 2, 1927

Inventor:
Lewis W. Evans,
by Alexander S. Hunt
His Attorney.

UNITED STATES PATENT OFFICE

LEWIS WILLIAM EVANS, OF PITTSFIELD, MASSACHUSETTS, ASSIGNOR TO GENERAL ELECTRIC COMPANY, A CORPORATION OF NEW YORK

ELECTRIC DISCHARGE DEVICE

Application filed December 2, 1927. Serial No. 237,285.

My invention relates to electric discharge devices; more particularly it relates to that type of such devices especially adapted for use as lightning arresters and the like.

5 Among the objects of my invention are to provide a discharge device of the so-called pellet arrested type with a construction which will insure against any dust from the pellet chamber reaching the spark gap chamber. Another object of the invention is to form one of the electrodes so that it may serve as a pellet container. Another object of the invention is to shorten that portion of the pellet column which resides within the 10 porcelain container located below the electrode on the side of the pellets.

Other details of the invention will appear from the following specification in which the means for accomplishing the results contemplated by the invention are fully set forth and claimed, reference being had to the accompanying drawing which shows a lightning arrester comprising the features of the invention.

25 The construction of the chamber 2, of the casing 3 enclosing said chamber, and of the upper portion of the arrester supported by said casing comprising the hoods 4 and 5, the terminal 6 and the upper electrode 7, is well known. The arrester is also provided 30 with a porcelain tube 8 which is hollow. Within the hollow portion, the usual column of pellets 9 is located. The lower portion of the arrester, that is, the porcelain member 35 8 with its hollow central portion and with the hood 10, together with the lower terminal element 11 is also well known. However, the lower electrode 12, as already indicated, forms one of the novel features of the invention. This electrode as shown is in the 40 form of an inverted cup provided with a flange 13 extending in a plane transverse to the axis of the electrode. The flange is in turn provided with an upturned rim 14. 45 The flange 13, as will be seen, rests on the upper end of the porcelain element 8. It will also be seen that the cup which forms the electrode 12 projects below the flange 13, the rim of the cup which thus projects 50 below the flange snugly fitting the opening

at the upper end of a metal tube 16 which extends down part way in the porcelain tube 8. As clearly shown in the drawing, the porcelain element 3 rests upon the rim 14 of the electrode 12, the porcelain element 3 being 55 provided with a channel for receiving the said rim. It will be further seen that a sealing material such as cement 15 is used to bind the element 3 to the element 8 and for sealing the space between the elements 3 and 8 60 adjoining the flange 13 and the rim 14 of the electrode 12. It will be seen, therefore, that because of this construction and because of the extension of the rim of the electrode 12 into the bore of the porcelain tube 8 so 65 as to insure a close fit, the electrode chamber 2 is insured against the leakage of any dust from the pellet chamber beneath and within the electrode 12, by a path around the flange 70 of electrode 12 into said chamber 2.

It is commonly the case that with the aging of the arrester the pellet column within the bore of the porcelain element 8 shrinks and therefore the pellet column shortens and the pellets gradually withdraw from the 75 bottom of the inverted cup which forms the electrode 12. With the old form of construction, this shrinkage of the pellet column was a very serious matter inasmuch as it affected the electrical connection between 80 the pellets and the electrode and in some instances a gap was formed between the pellet column and the under side of the lower electrode. Obviously, therefore, with the new form of construction described and shown 85 herein the shrinkage of the column will merely result in the end of the column receding slightly possibly from the bottom of the inverted cup. Inasmuch as the cup is made of substantial depth, satisfactory electrical connection is preserved between the 90 pellet column and the sides of the cup, notwithstanding the shrinkage of the column, thereby insuring permanent connection between the column and the electrode, notwithstanding 95 the use and age of the arrester.

It will be understood that while I have disclosed my invention in connection with a certain specific form of apparatus I do not 100 wish to be limited to such form inasmuch as

in view of the disclosure variations and modifications which do not depart from the spirit of the invention or from the scope of the claims contained herein will readily occur to those versed in the art.

What I claim as new and desire to secure by Letters Patent of the United States, is:—

1. In an electric discharge device, in combination, a pair of electrodes forming a spark

10 gap and a resistance column connected in series with said gap, one of said electrodes being hollow, said column projecting into the hollow section of said hollow electrode and forming electrical connection with the 15 inner sides of the said hollow electrode whereby connection may be maintained between the column and the hollow electrode notwithstanding a shrinkage of the column.

2. In a lightning arrester, in combination, 20 a pair of electrodes forming a spark gap therebetween, a column of resistance material formed of a mass of pellets, one of said electrodes being hollow and in the form of an inverted cup, said pellet column projecting 25 into said cup whereby the column may be moved with respect to the cup while maintaining electrical connection between the sides of the column and the inside walls of the cup.

3. In a lightning arrester, in combination, 30 a pair of electrodes forming a spark gap therebetween, a column of resistance material, one of said electrodes being hollow and in the form of an inverted cup, said resistance 35 column projecting into said cup, whereby the column may be moved with respect to the cup while maintaining electrical connection between the sides of the column and the inside walls of the cup, said cup being provided with 40 a flange extending transverse to the axis of the cup, a chamber enclosing the spark gap, a tube enclosing the lower part of said column and forming a column-containing chamber, said flange forming a partition separating the 45 two chambers, and a sealing material for sealing the spaces between the chambers to prevent any dust from the pellet chamber passing into the spark gap chamber.

4. In an electric discharge device, in combination, a pair of electrodes forming a spark gap, means for securing said electrodes in adjusted relation with respect to each other, a column of resistance material, and means for supporting one end of said column in a fixed 55 relation to one of said electrodes, the other end of said column being in variable physical relation but in permanent electrical connection with the same electrode, whereby a circuit connection may be maintained between the 60 column and the latter electrode notwithstanding shrinkage of the column.

5. In an electric discharge device, in combination, a pair of electrodes forming a spark gap, means for securing said electrodes in 65 adjusted relation with respect to each other, a

column of resistance material, and means for supporting one end of said column in a fixed relation to one of said electrodes, the other end of said column being in variable physical relation but in permanent electrical connection with the same electrode, whereby a circuit connection may be maintained between the column and the latter electrode notwithstanding shrinkage of the column, and said spark gap and column being sealed off with respect to each other, whereby dust from the resistance column is prevented from passing from the column to the gap.

6. In a lightning arrester, in combination, 70 a pair of electrodes forming a spark gap therebetween, a column of resistance material, one of said electrodes being hollow and in the form of an inverted cup, said resistance column projecting into said cup, whereby the column may be moved with respect to the cup 75 while maintaining electrical connection between the sides of the column and the inside walls of the cup, a tube enclosing the lower part of said column, said cup being provided with a flange extending transverse to the 80 axis of the cup, a chamber enclosing the spark gap and a chamber enclosing said column, the column chamber being formed by the hollow electrode and the tube, said flange forming a 85 partition between the two chambers, and means for sealing the chambers from each other about said flange.

In witness whereof, I have hereunto set my hand this 29th day of November, 1927.

L. WILLIAM EVANS.
